UNITED STATES PATENT OFFICE.

CHARLES H. TALLMADGE, OF BUFFALO, NEW YORK

MEANS AND METHOD FOR ACCOUNTING.

1,319,914.

Specification of Letters Patent.

Patented Oct. 28, 1919.

Application filed March 1, 1917. Serial No. 151,626.

To all whom it may concern:

Be it known that I, CHARLES H. TALLMADGE, a citizen of the United States, residing at Buffalo, in the county of Erie and State of New York, have invented a certain new and useful Improvement in Means and Methods for Accounting, of which the following is a full, clear, concise, and exact description, reference being had to the accompanying drawings, forming a part of this specification.

My invention relates to the art of accounting and more specifically is concerned with a novel method and apparatus for effecting algebraic summation.

Heretofore algebraic summation has been mechanically accomplished in two principal ways. One of the prior art methods contemplates the use of a so-called "algebraic totalizer" adapted to indicate the true algebraic sum of a plurality of positive and negative numbers entered thereon. Registers of this class comprise essentially a plurality of numeral wheels adapted for rotation in either direction, each numeral wheel having two series of figures thereon, one for positive and the other for negative indications, carrying mechanism between the several numeral wheels, some means for imparting a one-step movement to the figure wheel of lowest order when the resultant passes through zero, and a shutter for revealing one set of figures when the sign of the resultant is plus and the other set of figures when the sign of the resultant is minus.

In accordance with another and perhaps cruder method of algebraic summation a one-way register of ordinary construction is employed. According to this second method positive numbers are naturally entered upon the register, but in the case of negative numbers the complemental or co-digital equivalent thereof is entered upon the register, the array of nines revealed by the figure wheels of the higher orders being depended upon suggestively to indicate that the sign of the resultant is minus, when such is the case, and that the true resultant is not the one indicated but is in fact the complement of the indicated resultant. In most cases the array of nines revealed by the numeral wheels of the higher orders is amply sufficient to notify the operator of the negative nature of the resultant, since the

register is ordinarily of great capacity as compared with the magnitude of the numbers involved in the problems performed thereon. Thus, in a cash showing a reading of 99999990.85 would invariably be interpreted as an overdraft of \$9.15 rather than a real balance of \$99,999,990.85.

I have found that very frequently the positive or negative nature of the indicated resultant is either not in question or is so readily determinable that it is not necessary to employ an algebraic register or, in other words, a register which always indicates the correct algebraic resultant whether that resultant be positive or negative. However, in the past when simple one-way registers have been employed, as heretofore explained, the entry of a negative number is accomplished only by striking the keys in an abnormal manner in order to enter the complement of the negative number. While this has sometimes been governed wholly by mental translation, it has been a common practice to have the keys provided with co-digital red figures in addition to the ordinary and natural black figures. So far as I am aware, however, the method just described has been confined to ordinary adding machine work, except in the single instance where it is applied to card tabulating work. In card tabulating work the complemental or co-digital figures of the number to be subtracted are punched on the tabulating card with the result that the card is wholly inaccurate on its face and necessitates re-translation when it is considered in any other aspect than that of algebraic summation.

There may be other methods of algebraic summation but so far as I am aware they all depend upon or are associated with more or less special forms or combinations of registers or register attachments, or they depend upon changes in the direction in which the register numeral wheels are operated, or they depend upon a mental translation of a negative amount that is to be complementally entered in the register. My method of algebraic summation as herein-after described is not so limited. My method contemplates the use of an ordinary one-way register or cyclometer, and I prefer that negative amounts be key struck, entered, or set up naturally and without mental translation or correction.

2

My method is particularly adapted for card tabulating work and I shall therefore describe the details of my method in that connection. In carrying on this class of work I prepare cards based on the well known Hollerith or Powers plan with slight but extremely significant modifications, particularly in the case of negative amounts. The cards which I employ are particularly novel in that they are punched so that each card presents two opposing or complementary aspects. By placing the cards in a tabulating machine naturally and in the ordinary manner one aspect of the card is reflected in the resulting actuation of the tabulating machine totalizer, and by reversely placing the card in the tabulating machine the totalizer is actuated in accordance with the other aspect of the card. My invention, however, is not confined to the use of cards but is sufficiently broad to include other ways of securing algebraic results by making a set-up which has two aspects and utilizing the set-up in its normal aspect for natural accumulation and in its reversed aspect for complementary accumulation.

In addition to the improvements hereinbefore mentioned my invention contemplates other improvements, some of which are particularly adaptable for card tabulating work, while the others have a much wider application.

The various novel features of my new art and the apparatus I prefer to employ are fully set forth in the description to follow, wherein reference is made to the accompanying drawing, in which—

Figure 1 is a front view of one of the cards now usually employed in connection with the well known Hollerith tabulating mechanism;

Fig. 2 is a fragmentary view of the card shown in Fig. 1 having a certain number punched thereon;

Fig. 3 is a view showing the card of Fig. 2 reversed and placed upon a card similar to that shown in Fig. 1;

Fig. 4 is a view similar to Fig. 3 showing the upper card dropped two ranks of figures with respect to the lower card;

Fig. 5 is a fragmentary view of a card wherein the figure field is disposed in the upper five-sixths of the card face;

Fig. 6 shows the same card reversed and placed upon a card similar to that shown in Fig. 1;

Fig. 7 is a fragmentary view of a card having equal margins above and below the figure field, or, in other words, a card in which the figure field is centrally located with respect to the card face;

Fig. 8 shows the same card reversed and placed upon a second equal margined card;

Fig. 9 is a fragmentary view of an equal

margined card which is punched one unit short to effect the proper operation of the tabulating mechanism when the card is to be used for negative computation;

Fig. 10 is a view showing the same card 70 reversed and placed upon a second equal margined card;

Fig. 11 is a view of an equal margined card which is arranged to receive two sets of punching, one in a main column and one 75 in a supplemental column;

Fig. 12 is a view showing the card of Fig. 11 reversed and placed upon an equal margined card;

Fig. 13 is a view of an equal margined 80 card containing a dual punching in the units column;

Fig. 14 is a view showing the card of Fig. 13 reversed and placed upon a second equal margined card;

Fig. 15 is a view of an equal margined card containing two dual punchings, one in the units column and one in the tens column;

Fig. 16 is a view showing the card of Fig. 90 15 reversed and placed upon an equal margined card;

Fig. 17 is a view of a card dually punched in three orders, reversed and placed upon a second equal margined card;

Fig. 18 is a fragmentary view of an equal margined card showing a dual punching in the units column;

Fig. 19 is a view showing the card of Fig. 18 reversed and placed upon a second 100 equal margined card;

Fig. 20 is a diagrammatic representation of a contact box such as is employed in connection with the Hollerith tabulating mechanism, the units bank of contacts being 105 shifted or raised one step to effect proper operation of the totalizing mechanism when negative amounts are added to the totalizer;

Fig. 21 is a fragmentary front elevational view of an equal margined card to be used 110 in connection with the device illustrated in Fig. 20;

Fig. 22 is a view showing the card of Fig. 21 reversed and placed upon the contact mechanism illustrated in Fig. 20;

Fig. 23 is a diagrammatic representation of a circuit to be used in connection with a jack box or contact box as used on the Hollerith machine for changing the connections extending between the contacts and the 120 mechanism for operating the totalizing mechanism which in the Hollerith structure consists of electro-mechanical registering devices;

Fig. 24 is a fragmentary view of a tabulating machine for receiving the equal margined cards illustrated in Figs. 7 to 22 inclusive;

Fig. 25 is a fragmentary side elevational view of a punching apparatus arranged to 130

punch dually any column or columns of a card, some of the parts being shown in section to more clearly illustrate the construction;

5 Fig. 26 is a vertical cross sectional view taken along the line 26—26 of Fig. 25 looking in the direction indicated by the arrow;

10 Fig. 27 is a view similar to Fig. 24 of a tabulating device arranged to receive the card shown in Figs. 1 to 4 inclusive;

Fig. 28 is a diagrammatic view of a tabulating jack box and its coöperating pin box showing the same as electrically connected with the registering devices;

15 Fig. 29 is a fragmentary front view of an adding machine provided with a special key for transmitting to the units column of the totalizer a ten step movement or to the tens columns a one step movement when the complement of a number containing a zero in the units column is to be added to the number registered in the totalizer;

20 Fig. 30 is a fragmentary cross sectional view taken along the line 30—30 of Fig. 29 looking in the direction indicated by the arrows; and

25 Fig. 31 is a plan view of an adding machine which contains only one set of keys (0 to 9 inclusive) provided with a special key for imparting to the units wheel of the totalizer a ten step movement or to the tens wheel a one step movement when this is desired.

30 Similar characters of reference refer to similar parts throughout the several views.

Referring first to Fig. 1, 33 illustrates a card which is similar in all respects to the card now used in connection with the Hollerith tabulating device. The lower five-sixths of the card face contains a plurality of columns of numerals from zero to 9 inclusive, and the card in use can be divided into several fields or sets of columns, each field representing a certain commodity, a certain grade or a particular commodity, etc., depending upon the use to which the card tabulating system is put.

In Fig. 2 I have illustrated the card of Fig. 1 punched to represent the number 01234567. When this card is inserted into the tabulating mechanism of the system certain contacts representing the number 01234567 are closed with the result that the totalizer or cyclometer is actuated in a forward direction to add the number represented by the card. In Fig. 27 I have illustrated a portion of such a tabulator. The tabulator, in so far as adding the number represented by the card shown in Fig. 2 is concerned, forms no part of my invention and it will, therefore, be unnecessary for me to go into the mechanical details of the machine. It will suffice to point out generally the operation of the tabulator. In Fig. 27, 34 represents the framework upon which

is mounted a platform 35 arranged to support a plurality of cards 36 which are similar to the card shown in Fig. 1. The rear side of the stack 36 is supported by means of a plate 37 which is spring pressed so that it 70 normally tends to move to the right (Fig. 27). The support 34 carries a reciprocating member 38 provided with a finger 39 arranged to engage the front card of the stack 36. When the member 38 is moved downwardly, together with the finger 39, the first card of the stack 36 is gripped and pushed downwardly between the pair of rollers shown at 40. These rollers are then rotated to feed the card downwardly to the position 80 indicated at 41. Positioned on one side of the card 41 is a spring jack box 42 containing a plurality of spring jacks 43, one for each of the numbers provided on the card shown in Fig. 1. Mounted on the side of the 85 card 41 opposite the jack box is a pin box 44 containing a plurality of pins 45, one for each of the spring jacks 43. If desired an apertured plate 46 may be carried by the pin box, the outer end of each of the pins 45 90 projecting into one of the apertures contained by the plate 46. After the card has been delivered to the position indicated at 41 the pin box 44 is moved longitudinally toward the jack box 42 until the plate 46 95 presses the card 41 against the face of the jack box and the pins 45 either rest against the card 41 or project through the punchings and electrically connect with their co-operating spring jacks. This coöperation 100

between the pins 45 and the jacks 43 produces one or several electric circuits which energize suitable mechanism for advancing the registering devices or totalizer. In Fig. 28 I have illustrated diagrammatically the 105 circuit connections for operating the totalizer when the pins and jacks are connected. The electro-mechanical registering devices for advancing the totalizer are illustrated diagrammatically at 47, each registering device being arranged to advance one of the totalizer order wheels to enter a certain digit thereon. To prevent operation of the electro-mechanical devices when no card is inserted between the pin box and the jack 110 box a switch may be employed, as shown at 48. This switch consists of a spring 49 connected at 50 to the pin box and insulated therefrom. The free end of the spring 49 carries a contact arranged to engage a 115 plunger contact 51 normally held away from the spring 49 by means of a helical spring 52. The inner end of the plunger 51 extends toward the jack box and is arranged either to engage a card 41 or to pass through an aperture 53 provided in the jack box. If upon movement of the pin box toward the jack box a card is in position between the same the plunger 51 will engage the card and move to the left relatively to the 120 125 130

pin box to close on electric circuit between the pins 45 and the spring 49, the pins 45 being grounded, together with the plunger 51, to the box 44. If no card 41 is in position when the box 44 is moved toward the box 42 the inner end of the plunger 51 will be permitted to pass through the aperture 53 of the box 42 so that the contacts 49 and 51 are unaffected. The contact 10 49 connects with one side of a battery 54 while the other side of the battery is connected by means of a conductor 55 with one side of each of the electro-mechanical registering devices 47.

15 Since the spring jacks of the contact box 42 are similar in all respects to the card shown in Fig. 1, so far as the numerals contained thereon are concerned, I shall in the further explanation of my invention place 20 one card above another so that the resulting operation of the machine when the top card is inserted in a tabulator will be apparent. If, therefore, I take the card shown in Fig. 2 and place it directly on top of the card 25 shown in Fig. 1 the number 01234567 will be revealed. Therefore, the card shown in Fig. 2 may be used to add the particular number punched to the cyclometer of the tabulator. One particular feature of my invention, 30 however, has to do with using the card shown in Fig. 2 either to add the particular amount punched or to subtract the amount punched from the amount registered in the totalizer. If now I take the card shown in 35 Fig. 2 and reversely place it upon the card shown in Fig. 1, I have the number 76543210, which is neither the complement nor the co-digital of the number 01234567. Now by dropping the upper card two ranks, as 40 shown in Fig. 4, the number 98765432 (the codigital of 01234567) will be revealed. Thus by changing the tabulating mechanism so that the cards are held two ranks lower for negative amounts than they are for positive 45 amounts numbers punched on a card reversely placed in the tabulator may be subtracted from the amount in the totalizer (by co-digital addition) and the indicated resultant will be correct with the exception that it is lacking one unit for each of the negative cards so tabulated.

In Fig. 27 I have shown a tabulator which is arranged to receive the cards shown in Figs. 2 to 4 so that a number may be added 55 either naturally or co-digital. When the number represented by the card 2 is to be added naturally the support 56 is employed. When the number represented by the card 2 is to be entered reversely (in accordance 60 with its co-digital equivalent) the stop or support 57 is employed. The members 56 and 57 are preferably connected together so that when one is moved out of the way the other will simultaneously move into place. 65 The dotted lines 58 in Fig. 27 represent a

card reversed and resting against the stop 57 and thereby adapted for co-digital accumulation. Thus I am enabled to use a single card of the ordinary or commercial type, and by a few changes in the ordinary Hollerith tabulating machine obtain either a natural tabulation of the amount punched in the card or a co-digital computation by merely reversing the card and dropping it two ranks.

70 Fig. 5 shows a card in which the figure field is disposed on the upper five-sixths of the card face. The card shown in this figure is to be used for negative amounts only. If the card is punched to represent, for instance, the amount 257 and then reversed and placed upon the card 33 the number 742 will be revealed. Correspondingly, 742, the co-digital of the number 257, is entered in the totalizer when a card, conformed and punched as shown in Fig. 5, is reversely placed in the tabulator. Such negative cards will, however, have to be counted and the number thereof added to the register indication since the co-digital of the number punched on each of the cards is one unit 75 short of the complement.

80 Thus I may obtain a co-digital reading of a punched negative card in two ways, first, by reversing the card and then adjusting it to bring the figure field into proper reading and tabulating position, and, second, by initially adjusting the figure field of the card 85 before punching and then merely reversing the card after punching.

85 Fig. 7 shows a form of card in which the figure field is disposed centrally on the card to form what I shall refer to as an "equal 90 margined card." If on this card I punch the number 257 and reverse it upon a second equal margined card I obtain the co-digital 95 105 742. In this case the co-digital is obtained without shifting the cards one with respect to the other. It will also be observed that the card shown in Fig. 7 may be used either 110 to add naturally or to add co-digital, depending upon which side of the card is presented to the jack box of the tabulator. In Fig. 24 I have illustrated a tabulator arranged to receive the equal margined cards 115 just described. The tabulator shown in this figure is substantially identical with that shown in Fig. 27 with the exception that only one stop 59 is employed for holding the cards in proper position with respect to the 120 jack box. After the tabulator has made a record of the punchings of a card the stop 59 is moved from under the card to permit the latter to be delivered from the machine. This last mentioned mechanism forms no 125 part of the present invention and is employed in connection with the commercial Hollerith tabulator.

130 In employing all of the cards thus far described only the co-digital of the number to

be subtracted is added to the totalizer so that the resultant is one unit short for each of the negative cards passed through the tabulator. To overcome this objection and to 5 obtain a correct reading of all of the cards, whether positive or negative, I have devised several means, one of which is illustrated in Figs. 9 and 10. In Fig. 9 an equal margined card is used and the top of the card 10 printed or marked in some way so as to convey the idea that any number punched on the card is one unit short. For example, the card may contain the words "Negative card. Punched one unit short." If now, the card 15 shown in Fig. 9 is to be punched to represent the number 257 it is punched 256, as shown, so that when it is reversed and placed upon a second equal margined card, as shown in Fig. 10, the complement 743 will be revealed. 20 The card shown in Fig. 9 may, therefore, be used as a negative card and a correct reading will result in the totalizer. The card cannot, however, be used as a positive card since the number punched on the face of the 25 card is one unit short of the number 257. In Fig. 11 I have shown another form of equal margined card which is provided with two columns, *i. e.*, a right hand or a main column and a left hand or supplemental column. 30 When employing this form of card I use a tabulator having two cyclometers; one for the main column and one for the supplemental column. In punching the number 0257 in the main column a second 35 punching is made in the supplemental column, the second punching forming, in effect, a corrective punching to add one unit in the cyclometer of the supplemental column each time the card is passed through the tabulator 40 as a negative card. The top of the supplemental column is punched, as shown at 60, (the high X of the old tabulator art) so that when the card is inserted into the tabulator for positive accumulation certain contacts 45 will extend through the aperture 60 whereby the punching 9998 at the bottom of that column will be ignored. When the card is used as a negative card and is reversed, as shown in Fig. 12, the co-digital 9742 of the number 50 0257 will be registered in the main column and the co-digital of the number 9998 of the supplemental column will be added in the register or cyclometer assigned to the supplemental column. The aperture 60 55 when the card is reversed lies in a position below the "9" rank of contacts and since the tabulator is not provided with contacts at this position this aperture will simply be ignored. Each time that a negative card is passed through the tabulator 60 a unit will be added to the cyclometer controlled by the supplemental column so that after a plurality of both positive and negative cards have been passed through the 65 tabulator the indications of the two cyclome- ters are added together and the correct resultant obtained. If desired, different cards may be used for negative amounts than are used for positive amounts. In such cases the positive cards will not be punched 9998 70 in the supplemental column, but will be punched as shown at 60 so that this column is skipped by the tabulator. The negative cards will contain the co-digital punchings of the corrective unit 1 in the supplemental 75 column, but will not contain the punching 60 so that when the card is reversed the corrective unit 1 will be entered in the supplemental cyclometer.

Fig. 13 illustrates an equal margined card 80 which is punched dually in the units column. If the card shown in Fig. 13 is punched to represent the number 257 a second punching is made at 6 in the units column so that the card will represent in effect the two numbers 256 and 257. As is well known, the Hollerith tabulator is arranged so that it will recognize only the lower one of several punchings in a given column. As a result, if the card shown in Fig. 13 be passed 85 through the Hollerith tabulator in the natural way the number 257 will be added to the totalizing register. If now the card shown in Fig. 13 be reversed and placed upon a second equal margined card, as 90 shown in Fig. 14, there will be revealed a number of digits which may be interpreted as either 742 or 743. Inasmuch as the 3 in the units order lies below the 2, the complement (743) of the number 257 will be entered upon the tabulator register, when the card is placed reversely in the tabulator; this for the reason that the Hollerith machine recognizes only the lowermost punching in any order. 95

The ordinary tabulator is of course not arranged to effect more than nine steps digitization in the units order of the register so that when a card is dually punched for 0 in the units column, as shown in Fig. 15, the 100 extra punching will lie above the 0 rank (as at 0), and when the card is reversed the extra punching will lie in a position which I shall refer to hereinafter as "Z". In Fig. 15 the card is punched to represent the number 105 40 and since dual punching for the 0 in the units column affords an extra punching which when the card is reversed lies at "Z" below the 9 rank it is necessary to punch dually the tens column, or, in other words, 110 40 to punch the 3 directly over the 4 in the tens column. If now the card is reversed, as shown in Fig. 16, and placed in a tabulator, the "6" and "Z" holes control the register 115 since the tabulator recognizes only the lowest punching. In using this form of card and this method of punching I intend to make a slight change in the tabulator so that when it recognizes the "Z" punching in one of the columns it will simply ignore that 120 125 130

column, or, in other words, will do exactly the same at it does when it recognizes a 0 punching.

In Fig. 28 I have shown in dotted lines a contact pin 61 and a coöperating jack 62, the latter being connected by a conductor 63 with a conductor 64 connected in turn with the zero electro-mechanical registering device 47 corresponding with the order represented by jack 62. When the card shown in Fig. 15 is reversed and placed in the tabulator, the complement of the number 40 will be added to the totalizer indication. If the number punched contains more than two zeros, as in Fig. 17, which represents a card punched 400, the first two columns will be dually punched, as will also the third, so that the tabulator will recognize two Z punchings and ignore the two columns corresponding with the Z punchings. In the third column the digit 6 (the complement of 4) will be recognized by the tabulator.

The system last described necessitates the employment of dual punchings in more than one column. To avoid this dual punching in more than one column I may employ the system illustrated in Figs. 18 and 19 in which only one dual punching is necessary and this only in the units column. In Fig. 18 an equal margined card is punched to represent the number 71420, the units column being dually punched, one punching being one number short of the number represented by the card. When the card is reversed upon a second equal margined card, as shown in Fig. 19, the contacts which I shall refer to hereafter as the X contacts are allowed to pass through the lower one of the punches in the units column. The tabulator will be arranged with the usual ten spring jacks and contact pins with the exception that in the units column an additional spring jack and coöperating pin will be provided to extend through the punching shown at X in Fig. 19. This spring jack and contact pin are connected with the electro-mechanical registering device which when actuated either adds 10 to the units wheel of the register or adds 1 to the tens wheel of the register. This electro-mechanical registering device is similar in all respects to the devices now employed, except that it advances the register ten steps in the units column or one step in the tens column. In employing this arrangement the number represented by the card shown in Fig. 18 is added naturally to the register when the card is presented in the usual way to the tabulator. When the card is reversed and inserted in the tabulator the complement of the number 71420, which is 28580, is added to the register so that in so far as the indicated resultant is concerned the original number has been subtracted from the register and the answer which results from such

actuation of the register is correct in all respects.

Figs. 20 to 22 illustrate a system in which a special tabulator is used for negative cards. Fig. 20 illustrates diagrammatically a portion of the spring jack box of the tabulator. Attention is called to the fact that the units column of contacts is shifted upwardly one rank so that the contact assigned to the digit 1, of units order lies opposite the contact assigned to zero in tens order, units 2 opposite tens 1, etc., the contact assigned to digit 9 in tens order lying opposite the contact "X," in units order which represents ten units.

Fig. 21 illustrates a card punched to represent the number 960. When this card is reversed and placed upon the contacts of Fig. 20, as shown in Fig. 22, the holes in the card will be presented to the contacts 03X of the tabulator. Thus by shifting the units order of tabulator contacts the corrective unit is added without the necessity of dually punching the card or of later adding a corrective punching, as is necessary in the system described in connection with Figs. 11 and 12. The construction just referred to necessitates the use of two tabulators, one for positive amounts, and the other for negative amounts, although one card may be used for either positive or negative amounts.

To avoid the necessity of providing two such tabulators the system disclosed diagrammatically in Fig. 23 may be employed. In this figure each of the several conductors, numbered 0 to 9 inclusive, extends from a switch 65 to its corresponding spring jack in the units column. The several switches 65—65 are pivoted, as shown, at 66 to a longitudinally movable rod 67 pivoted to a lever 68 in turn mounted upon the pivot point 69 for oscillation. When the lever 68 is in the position shown in full lines the several switches will be held in the position shown so that the 0 spring jack is electrically connected with the 0 electro-mechanical registering device, the 1 spring jack electrically connected with the 1 electro-mechanical registering device, etc. When, however, the lever 68 is moved from its full line position to the position shown in dotted lines all of the several switches 65 will be moved about their pivots to the positions indicated by the dotted lines so that the 0 spring jack of the units column is electrically connected with the 1 electro-mechanical registering device, the 1 spring jack electrically connected with the 2 electro-mechanical registering device, and so on, so that when the lever 68 is moved to the negative position the jacks of the units column on the tabulator will add 1 more in the register than they do when the lever 68 is set for positive cards. When the lever 68 is set for negative accumulation the lower switch blade 65 of the 9 spring jack

will electrically connect with the 10 electro-mechanical registering device so that when the 9 spring jack and its coöperating pin are electrically connected a circuit will be completed through the 10 electro-mechanical registering device to add 10 in the units wheel or 1 in the tens wheel of the totalizer. By the employment of the construction shown in Fig. 23 it is necessary to employ only one tabulator and the cards may be punched in their usual way, that is, without any corrective punching and without any dual punchings. The card is moreover correct on its face and may be read directly without mental correction.

In Figs. 25 and 26 I have illustrated a machine for effecting the dual punching required in connection with the cards shown in Figs. 13 to 19 inclusive. The construction shown in Figs. 25 and 26 is somewhat similar to the Hollerith punching device in that a single set of keys, 0 to 9 inclusive, is employed for punching the card. The card is arranged to travel longitudinally under the punching mechanism so that but one vertical column of figures on the card is presented to the punching mechanism at any one time. After a punching operation has taken place the card is automatically moved one step so as to enable the next vertical row to be punched. Although the dual punching mechanism of my invention may be applied to different types of punching machines, such, for example, as a machine which contains several sets of keys, I have, for the sake of illustration, applied it to the Hollerith ten key machine.

In Fig. 25, 82 illustrates the casing of the punching machine and 83—83 a plurality of levers each pivoted at 84 to the support 82. Each of the levers 83 has mounted at its free end a key 85 arranged so that when pressed downwardly its associated lever 83 will be rotated in a clockwise direction (Fig. 25). Extending transversely of the levers 83 and under the same is a block 86 containing a plurality of bores 87 in each of which is reciprocably mounted a plunger or punch member 88. Normally to hold these punch members 88 in the position illustrated in Fig. 26 a helical compression spring 89 is employed for each of the members, the tendency of the springs being to move the members 88 upwardly. The underside of each one of the levers 83 carries an extension 90 arranged to coöperate or rest against the upper face of one of the punch members 88. The card to be punched, shown at 91, is disposed directly under the plungers 88 so that upon downward movement of the plungers, or any one of them, a punching will be made on the card, the downward movement of the plungers 88 being effected by pressing the desired keys 85. After each punching operation suitable

mechanism is employed for moving the card 91 to the left (Fig. 25), so that the next vertical rank of figures is presented to the plungers. This mechanism for moving the card longitudinally forms no part of the present invention and it is, therefore, considered unnecessary to go into the details of this construction. Whenever it is desired to effect a dual punching in any one or more of the vertical columns of figures on the card 91 the key 92 is first pressed, whereupon the pressing of any one of the other keys 85 accomplishes a dual punching, a punching of the number represented by the pressed key 85 and the automatic punching of the number which is one unit less than the number represented by the depressed key 85. The key 92 is attached at its lower end to a bell crank lever 93 pivoted at 94 to the casing 82. The upper end of the bell crank lever 93 is pivotally connected at 95 with ten arms 96 normally held in the horizontal position shown in Figs. 25 and 26 by means of any suitable mechanism such, for example, as the lugs 97 formed on the upper end of the bell crank lever 93. Each one of the arms 96 is arranged so that when the key 92 is depressed said arm will be moved to the position indicated by the dotted lines in Fig. 25. When in this position each of the arms 96 rests directly above two of the plungers or punch members 88, as most clearly shown in Fig. 26. Attention is directed to the fact that each one of the projections 90 is notched, as shown at 98, so that when the key 92 is depressed each one of the arms 96 fits into the notched portion of one of the projections 90. In making a dual punching on a card the key 92 is first depressed, as hereinbefore pointed out, and the desired key 85 pressed. If we assume that it is desired to punch the numeral 4 on the card the 4 key is then depressed. By referring to Fig. 26 it will be observed that upon depression of the lever 83 connected with the 4 key the projection 90 associated with the lever 83 will be moved downwardly to depress the plunger 4. On account of the notch provided in the last mentioned projection 90 the arm 96 disposed in the notch will also move downwardly and since this arm is disposed above the plunger 88 for punching the numeral 3 this plunger will be actuated simultaneously with the plunger for punching the numeral 4. After a dual punching has been made in one of the vertical numeral columns of the card and it is desired to make only a single punching in the next vertical column the key 92 is released or pulled upwardly to move the arms 96 away from the several plungers and back into the position shown in full lines in Fig. 25.

Although I have described and shown in

Figs. 25 and 26 an automatic dual punching machine it will readily be apparent that the dual punching may be accomplished by the pressing of the two keys corresponding with the two numerals to be punched. It is also apparent that the extra punching, or corrective punching, may be accomplished by means of a hand punch after the card has been punched for natural tabulation.

10 In Figs. 19, 20, 22, and 23 I have disclosed diagrammatically a card tabulating machine which contains an "X" contact for complementary tabulation, the purpose of the "X" contact being to impart either ten steps to 15 the units wheel of the register or one step to the tens wheel of the register when such contact is operated. This arrangement is broadly new so far as I am aware and I, therefore, do not desire to limit myself to 20 the use of this arrangement in a card tabulator. In Figs. 29 to 31 inclusive I have shown this general arrangement applied to an adding machine wherein subtraction is 25 accomplished by adding the complement of a number to be subtracted to the number in the totalizer. In Fig. 29 I have illustrated a face view of an adding machine keyboard. The several keys are shown at 99-99 and the totalizer or register at 100. 30 The several keys 99 in the columns other than the units column are marked in the usual way (as in black) and for complementary work the co-digital (in red) of the number represented by the key is also placed 35 upon the key, as illustrated. For example, the 0 key is marked with a comparatively large 0 and, preferably at the left side, is marked with its co-digital 9, and so on. In the units column, however, the several 40 keys are marked with their complements with the exception of the 0 key. The units column is provided with an extra key, (corresponding to the "X" contact) as shown at 101, which is marked 0 and is to be used only 45 for complementary work. The depression of this key adds either 10 in the units wheel of the register or 1 in the tens wheel thereof. In subtracting a number the keys containing 50 the small figures representing the number to be subtracted are depressed so that the complement of the number is added in the totalizer. If the number to be subtracted contains a 0 in its units order the special key 101 is depressed with the result that a 55 carry-over is effected between the units wheel of the register and the tens wheel. The marking of the units column of keys 99 in a complementary manner avoids the necessity of doing any mental calculation whatsoever, it being necessary only to depress the 60 keys which contain the small numerals corresponding with the number to be subtracted.

In Fig. 30 I have illustrated diagram-

atically the operation of the adding machine shown in Fig. 29. Fig. 30 is a cross sectional view taken along the line 30-30 of Fig. 29 and shows the units column of keys. The keys are all slidably mounted in a top plate 102 and are normally held in their up positions by means of the several springs shown at 103. Disposed under each order of keys is a gear sector 104, pivoted at 105 to the casing of the machine and meshing with a gear wheel 106 of the totalizer. 107 represents diagrammatically the carry-over mechanism interposed between the several numeral wheels of the totalizer. The upper side of each one of the gear sectors 104 is provided with a plurality of 80 steps 108, each step being engaged, or arranged to be engaged, by one of the several keys of one order. The 0 key need not be arranged to do anything to the gear sector upon depression since the adding of the 0 85 does not affect the totalizer. The 1 key, however, imparts to the gear sector 104 a one step movement in a counter-clockwise direction (Fig. 30) with the result that the totalizer is advanced one step, the 2 key advances the gear sector two steps, and so on. The special key 101 is located below the 9 key and upon depression of the former the gear sector 104 will be given a ten step 90 movement with the result that a ten step 95 movement is imparted to the units numeral wheel.

In Fig. 31 I have illustrated a face view of the keyboard used on machines wherein only one set of keys, 0 to 9 inclusive, is used for 100 addition or subtraction. In this case the several keys are co-digitally marked so that subtraction may be accomplished complementary. The key 109 is the special key corresponding to the key 101 shown in Figs. 105 29 and 30, and performs the same function as does the key 101. Since I have illustrated the operation of the key 101, in Figs. 29 and 30, it will suffice to say that upon depression of the key 109 the units wheel of 110 the totalizer of the machine shown in Fig. 31 will be given a ten step movement or the tens wheel a one step movement.

So far as I am aware it is broadly new with me to effect a register controlling set-up 115 which has two distinct aspects, one obverse or natural for positive accumulation, the other reverse or complementary for negative accumulation. In applying the method of my invention to card tabulating work I 120 punch the set-up upon a card which has the two aspects before mentioned. While, as hereinbefore pointed out, I prefer to utilize an equal margined card for carrying out my method in card tabulating work, and while 125 I believe I am the first to employ such a card, it is not absolutely essential that such a card be utilized. It is possible to utilize

two aspects of a set-up punched upon the usual tabulating card provided the ordinary tabulating machine is modified in certain slight but significant respects.

5 My improved method makes it possible to so punch the cards that the numbers represented by the punchings thereon may be determined at a glance. Thus, although a card when used reversely, causes the tabulating machine totalizer to be advanced in accordance with the complement or co-digital of a certain number, the true value of that number may be determined merely by glancing at the face of the card.

15 Inasmuch as I am the first to employ a tabulating machine card set-up having the two aspects hereinbefore mentioned it follows the dual punching in the units order to take care of the corrective unit when the 20 card is utilized for negative accumulation is also new with me. This dual punching would seemingly have no function nor even be tolerable in any other method than mine.

Furthermore, I believe that I am the first 25 to suggest an arrangement for advancing the units wheel of a totalizer ten steps (or the tens wheel one step) when in complementary accumulation there is a zero in the units order of the number the complement of 30 which is to be accumulated. I have pointed out the advantages of this arrangement and its adaptability to ordinary adding machines as well as to card tabulating machine work.

35 It will be apparent that the novel features of my invention are capable of wide application. Therefore, I do not limit myself to the precise details of the apparatus herein shown nor to the administrative details of the several variations of my improved method. As has been hereinbefore pointed out, my novel set-up has two aspects, one "natural," the other "co-digital" or "complemental." In so far as the appended claims are concerned the term "complemental" is to be interpreted broadly enough to include "co-digital" unless the contrary is specifically pointed out in the claim.

45 50 What I claim as new and desire to secure by Letters Patent of the United States, is:

1. The herein-described method which consists in punching a certain set-up on a card, presenting one face of the card to the card reading elements of a register actuating device for direct accumulation and presenting the other face of the card to said reading elements for complemental accumulation.

55 60 2. The herein-described method which consists in punching a certain set-up on a card representing the digits of a number to be entered in a register mechanism and presenting the card to the card reading ele-

ments of a register actuating mechanism in 65 such a manner that the register is actuated by said set-up in accordance with the complement of the number set up on said card.

3. The herein-described method which consists in forming a set-up to represent the 70 digits of a number by punching holes in a card, employing indicia on one face of the card for locating the holes and presenting the other face of the card to the card reading elements of a register actuating mechanism for complemental accumulation. 75

4. The herein-described method which consists in punching a card one unit short of the set-up represented thereby and presenting the card reversely to the card reading elements of the register actuating device for complemental accumulation. 80

5. The herein-described method which consists in punching holes in a card at points determined by indicia arranged thereon in 85 ranks and files, presenting one face of the card to the card reading elements of a tabulating machine for natural accumulation and presenting the other face of the card to the reading elements for complemental 90 accumulation.

6. The herein-described method which consists in punching holes in a card at points located by indicia on one face thereof and presenting the other face of the card to the 95 card reading elements of a tabulating machine for complemental accumulation.

7. The herein-described method which consists in so locating the set-up holes on one face of a tabulating machine card that when 100 the reverse side of the card is presented to the card reading elements of a tabulating machine the tabulating machine totalizer is actuated in accordance with the complement of the number represented by said holes. 105

8. The method which consists in punching a set-up upon an equal margined tabulating machine card having indicia arranged thereon in ranks and files and presenting the reverse face of the card to the card reading 110 elements of a tabulating machine for complemental accumulation.

9. An equal margined tabulating machine card to be used for positive and negative summation. 115

10. A tabulating machine card to be used for both positive and negative summation having equal margins at top and bottom.

11. A tabulating machine card to be used for both positive and negative summation 120 having indicia arranged thereon in ranks and files, said card having equal margins at top and bottom.

12. A tabulating machine card having equal margins at top and bottom and 125 punched to represent a certain set-up, said card adapted to cause a tabulating machine totalizer to be actuated naturally when the

obverse face of the card is presented to the card reading elements of the tabulating machine and complementally when the reverse face is presented to the card reading elements.

- 5 13. A tabulating machine card having punched thereon a set-up having two distinct and opposing aspects, one natural, the other complemental.
- 10 14. A tabulating machine card having indicia arranged in ranks and files on one face thereof, said indicia so arranged that the ranks and files register with the card reading elements of a tabulating machine when the reverse face of the card is presented to said card reading elements.
- 15 15. A tabulating machine card having indicia arranged in ranks and files on one face thereof, said indicia so arranged that the several ranks and files register with the
- 20

card reading elements of a tabulating machine when either face of the card is presented to said card reading elements.

16. The combination with a card having holes punched therein in positions to indicate the digits of a number of a register mechanism provided with means for co-acting with the holes in said card to enter the number indicated by the holes when the card is presented to the register mechanism 25 in one position and for entering the complement of the number when the card is presented in another position.

In witness whereof, I hereunto subscribe my name this 15th day of February, A. D. 30 1917.

CHARLES H. TALLMADGE.
